UNITED STATES PATENT OFFICE.

CHARLES F. GRAY, OF SIERRA MADRE, CALIFORNIA, ASSIGNOR TO THE SINGER
MANUFACTURING COMPANY, A CORPORATION OF NEW JERSEY.

SEWING-MACHINE.

1,346,884.

Specification of Letters Patent. Patented July 20, 1920.

Application filed March 24, 1919. Serial No. 284,789.

To all whom it may concern:

Be it known that I, CHARLES F. GRAY, a citizen of the United States, residing at Sierra Madre, in the county of Los Angeles 5 and State of California, have invented certain new and useful Improvements in Sewing-Machines, of which the following is a specification, reference being had therein to the accompanying drawings.

This invention relates to improvements in guides, especially such as binders, folders and the like, for use in connection with sewing machines and more particularly with sewing machines employing an endwise reciprocating needle mounted for bodily lateral movements, as for instance in so termed needle-feed sewing machines wherein the needle moves bodily laterally during the feeding of the material, thereby maintaining the several plies of material being stitched in definite relation.

In the employment of guides in sewing machines of the class referred to, it has heretofore been the practice to secure the guide 25 on the cloth-plate or work-cylinder as close as practicable and in advance of the point of penetration of the material by the needle. As the needle then moved bodily away from this point during the feed of the material it 30 was impossible to at all times sharply turn the work, as the material was held at two spaced points.

The present invention has for its object to obviate this difficulty inherent in machines 35 as described and to provide a sewing machine having an endwise reciprocating and bodily laterally movable needle with a guide maintaining a substantially definite spaced relation with respect to the needle throughout the lateral movements of the latter.

In the preferred embodiment of the present improvement, the sewing machine mechanism employed is substantially as disclosed in the United States patent to Albert 45 Rontke, No. 989,538, dated April 11, 1911, employing an oscillating feed-actuating frame in which the needle-bar is journaled for reciprocating movements and upon which the feed-dog is secured. It is to be understood however that the invention is

not limited to a sewing machine employing this mechanism, but is equally applicable to other types of sewing machines embodying bodily laterally movable needles.

In accordance with the present construction and in order to maintain the definite relation referred to with the needle, a guide in the present instance in the form of a binder is carried by a supporting plate suitably fulcrumed at a point substantially in alinement 55 with the fulcrum of the oscillating feed-actuating frame. A stud carried by the binder-supporting plate projects downwardly into an aperture in the feed-bar, insuring lateral movements of the binder with 60 the needle. The binder is positioned closely in advance of the needle and inasmuch as it maintains this relative position throughout the feeding movements of the needle, it is practicable to turn the work to stitch around 65 sharp curves.

In the accompanying drawings, Figure 1 is a front sectional elevation of a sewing machine embodying the present improvement. Fig. 2 is a view of the sewing machine in front end elevation. Fig. 3 is a top plan view of the work-arm, presser-foot and feed-foot. Fig. 4 is a view similar to that of Fig. 3, but omitting the presser-foot and feed-foot and with the binder-supporting plate partly cut away.

Inasmuch as the sewing machine mechanism illustrated in the accompanying drawings is constructed substantially as fully shown and described in the prior U. S. Patent No. 989,538 hereinbefore referred to, reference will be made to only such portions thereof as is deemed essential to an understanding of the present invention.

Referring to the drawings, the sewing machine comprises a work-arm or cylinder 1, from which rises the hollow arm-standard 2 and overhanging bracket-arm 3 terminating in the head 4. Journaled in suitable bearings provided in the arm-standard and overhanging bracket-arm is the main or needle-bar actuating shaft 5 carrying at one end the usual belt-wheel 6. The main-shaft 5 also carries the pulley 7, connected by means of the belt 8 with the pulley 9 secured upon 90 95 100

the looper-actuating shaft 10, suitably journaled in bearings provided in the work-cylinder 1 and carrying the loop-taker 11.

At its forward end, the main-shaft 5 carries the flange 12 in which is secured, by means of the screw 13, the crank-stud 14 embraced by the sleeve 15 on one end of the link 16. The other end of the link 16 is provided with a sleeve 17 entered by the pin 18 projecting from the collar 19 suitably secured upon the needle-bar 20, carrying the needle 21. By means of this construction, endwise reciprocatory movements are imparted to the needle-bar 20, which is journaled in vertically alined apertures formed in the oscillating feed-frame 22.

The feed-frame 22 is mounted to oscillate upon oppositely arranged pivotal bearings comprising the fulcrum stud 23 threaded into the overhanging arm, and pivot-pin 24, secured by the screw 25 in the arm 26 of said feed-frame and entering an aperture 27 formed in the work-cylinder 1. To the forward end of the arm 26 of the feed-frame 20 is secured by means of the screw 28 the feed-bar 29 having a raised serrated portion or feed-dog 30 and a needle-aperture 31. The feed-frame 22 receives its oscillating movements from an eccentric 32 on the main-shaft 5, embraced by a strap 33 having an apertured boss 34 adapted to be entered by a pin 35. The pin 35 is formed or otherwise provided at its lower end with an eccentric portion 36 which is adjustably secured by means of the screw 37 in the apertured ear 38 provided on the feed-frame. The eccentric 32 may be adjusted to vary the feed by means of the rod 39 in a manner well known, and as fully shown and described in the U. S. patent to W. F. Dial *et al.*, No. 718,988, May 27, 1903.

Pivottally mounted upon the work-cylinder on an axis substantially in alinement with the axis of oscillation of the feed-frame 45 22 is the supporting plate 40 of a guide in the form of a binder 41 adjustably secured to said supporting plate by screws, as 42. This supporting plate serves also as a cover for the work-cylinder and it is provided 50 with an aperture entered by the pivot-pin 24. Threaded into the pivot-pin 24 is a screw 43 between the head of which and the supporting plate 40 is interposed a coiled spring 44 to yieldingly hold the supporting plate in position upon the work-cylinder. The binder herein shown is of that well known type styled as "British" binders, but it is to be understood that the invention is not limited to this type of binder. It will 55 be observed that the binder-head is partially cut away to permit its positioning closely adjacent to the needle and that by means of a stud 40', projecting downwardly from the supporting plate and adapted to enter an aperture 29' in the feed-bar, the needle 21,

feed-dog 30 and binder 41 maintain a definite lateral relation with respect to each other thereby permitting the turning of sharp corners, at the same time obtaining the advantages inherent in a needle-feed machine by preventing relative movement of the body and binding materials during the feed of the same. Owing to the distance of the axis of oscillation of the feed-frame from the needle, it is obvious that the pivotal point of the binder might be slightly offset from said axis of oscillation without to any great extent interfering with the effectiveness of the relatively positioned needle and binder.

Movable laterally with the feed-dog 30 is the step feeding-foot 45 carried by the feeding-foot bar 46 journaled for vertical movement in the feed-frame 22. The vertical reciprocations of the feeding-foot 45 alternate with like movements of the presser-foot 47, the alternate reciprocations of these elements being caused by mechanism such as fully shown and described in the patent to Rontke, No. 989,538 before referred to or by any other suitable mechanism of a like character which are well known in the art. The feeding foot 45 is partly cut away at 48 to permit of close adjustment of the cut-away binder relative to the needle. The binding 45 is led between tension-pins, as 49 from a suitable supply holder, through a guide 50 which imparts an initial fold to the fabric and thence to the binder 41.

In the operation of the sewing machine 100 and during the feeding movement of the needle, the binding is held by the needle positively in position upon the margin of the body-fabric, the feeding foot 45 contacting with the work and the presser-foot 47 being raised. During the return movements of the feed, the feeding foot is raised and the presser-foot contacts with the work. The return movement of the binder at this time and the holding of the binding and body-fabric by the presser-foot draws the binding through the binder and stretches it closely over the margin of the body-fabric. The needle now pierces the work and maintains this relation of the binding and body 110 fabric.

The present machine therefore includes the well known features of maintaining the binding and body fabric in the desired relative positions, and stretching the binding 120 closely about the edge of the body fabric in addition to the improved feature of permitting the turning of sharp corners by maintaining a substantially constant position relatively to the needle and the binder. 125

Having thus set forth the nature of the invention, what I claim herein is—

1. In a sewing machine, the combination with an endwise reciprocating and bodily laterally movable needle, and means for im- 130

parting said movements to the needle, of a binder, and means for actuating said binder to maintain a substantially constant position relative to the lateral positions of said 5 needle.

2. In a sewing machine, the combination with an endwise reciprocating and bodily laterally movable needle, means for imparting said movements to the needle, a feed-dog, and means for imparting feeding movements to said feed-dog in timed relation with respect to the lateral movements 10 of the needle, of a binder, and means for actuating said binder to maintain a substantially constant relative position with respect to the lateral positions of said needle.

3. In a sewing machine, in combination, a needle, means for reciprocating said needle, a feed-dog, means for imparting feeding movements to said feed-dog, a binder, and means for moving said binder with said 20 feed-dog, whereby the movements of the feed-dog and binder remain substantially in parallelism.

25 4. In a sewing machine, in combination,

a needle, means for endwise reciprocating said needle, a binder, and means for imparting bodily lateral movements to said needle and to said binder upon axes substantially in alinement.

30

5. In a sewing machine, in combination, a needle, means for endwise reciprocating said needle, a feed-dog, a binder, and means for imparting lateral movements to said needle, feeding movements to said feed-dog 35 and bodily movements to said binder upon axes substantially in alinement.

6. In a sewing machine, in combination, an endwise reciprocating needle, means for reciprocating said needle, means for imparting bodily lateral movements to said needle, a binder and connections intermediate said last named means and said binder for maintaining the binder at a substantially constant distance from said needle 40 throughout the lateral movements thereof.

45 In testimony whereof I have signed my name to this specification.

CHARLES F. GRAY.
